UNITED STATES PATENT OFFICE

108,016

DESIGN FOR A BOX FOR CIGARETTES, PLAYING CARDS, AND THE LIKE

Harvey Lathrop, Forest Hills, Long Island, N. Y.

Application November 18, 1937, Serial No. 72,986

Term of patent 7 years

To all whom it may concern:

Be it known that I, Harvey Lathrop, a citizen of the United States, residing at Forest Hills, Long Island, county of Queens, State of New York, have invented a new, original, and ornamental Design for a Box for Cigarettes, Playing Cards, and the like, of which the following is a specification, reference being had to the accompanying drawing, forming part thereof.

ing my new design, the same being shown in closed condition;

I claim:

The ornamental design for a box for cigarettes, playing cards, and the like, substantially as shown.

HARVEY LATHROP.
